UNITED STATES PATENT OFFICE.

CHARLES DRAKE, OF MANNINGTON, WEST VIRGINIA.

CLOTHES-DRIER.

SPECIFICATION forming part of Letters Patent No. 603,132, dated April 26, 1898.

Application filed April 24, 1897. Serial No. 633,610. (No model.)

To all whom it may concern:

Be it known that I, CHARLES DRAKE, of Mannington, in the county of Marion and State of West Virginia, have invented a new and useful Improvement in Clothes-Driers, of which the following is a full, clear, and exact description.

The object of my invention is to provide a clothes-drier of exceedingly simple, durable, and economic construction and which may be mounted upon a support or upon a bracket or suspended from an overhead support and turned readily either to the right or to the left.

Another object of the invention is to construct a drier in an economic manner and so shape it that it may be placed in a position to occupy but little room in storage.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in both the figures.

Figure 1 is a sectional view through the drier, taken substantially on the line 1 1 of Fig. 2, a portion of the support for the drier being likewise in section; and Fig. 2 is a plan view of the drier and the support shown in Fig. 1.

The body A of the drier is preferably made as illustrated, in which it is shown as formed of one piece of wire of the requisite thickness, which is bent upon itself to form a helical coil, the wire at the center being carried downward and bent upon itself to provide a vertically-disposed eye 10 and a pin 11 below the eye. The members of the coil are strengthened, and the coils are prevented from sagging to too great an extent by connecting the members of the coil with cords or light wires 12, which extend radially from the center, as is particularly shown in Fig. 2.

In the drawings the clothes-drier is shown as carried by a support consisting of legs 13, arranged to form a tripod, the tripod being pivotally connected at its upper end with the body portion 14 and the legs being limited in their outward movement by means of wires or other flexible braces 15, located near the central portions of the legs. The body or

block 14 of the support in this instance has an opening in its top, which receives the pin 11 of the drier, the eye resting on the top portion of the block or body, as illustrated in Fig. 1, whereby the drier proper is held in a horizontal position and may be freely revolved to the right or to the left, as required. 55

The flexible braces or strings 12, connecting the coils of the helix, prevent said helix from springing or stretching downward when suspended at the top farther than the adjustment of the braces will allow. The braces also support all the excess of load above that 65 which is supported by the elasticity of the wire of which the helix is made.

When the device is not needed, it is flattened and may be stood up against the wall, occupying but little room. 70

I desire it to be understood that the coil from which the body of the drier is made may be given any shape without departing from the spirit of the invention—as, for example, it may be polygonal, diamond, or of triangular formation. It is evident that clothes hanging on any section of the helical body do not hang immediately over or under another section, and hence the air can have free access to all the garments and all parts of the 80 drier.

Having thus described my invention, I claim as new and desire to secure by Letters Patent—

1. A clothes-drier, consisting of a wire bent 85 into a helix, the inner end thereof extending to the center and being bent to form an eye, lying in a plane perpendicular to the plane of the helix, then extending perpendicular to the plane of the helix, the extreme end thereof 90 forming a pivot upon which the whole may revolve, substantially as described.

2. A clothes-drier, consisting of a wire bent into a helix, the inner end thereof terminating in a pivot which is perpendicular to the 95 plane of the helix and is connected to the body of the helix by a laterally-extending eye which acts as a shoulder, and a series of radially-extending connectors attached to the coils of the helix and limiting their relative 100 movements, substantially as described.

3. A clothes-drier, consisting of a wire bent into a helix, the inner end thereof extending to the center and being bent to form an eye

lying in a plane perpendicular to the plane of the helix and then extending perpendicular to the plane of the helix, the extreme end thereof forming a pivot upon which the whole 5 may revolve, and a folding stand having a socket in its upper end adapted to receive said pivot and to support the helix, substantially as described.

4. A clothes-drier, formed of a single wire

bent into coils of successively-increasing size, the coils being joined by radial braces or connectors, and a central supporting pivot formed upon the inner end of said wire, substantially as described.

CHARLES DRAKE.
